JOHN J. McBRIDE, OF BAYONNE, NEW JERSEY, ASSIGNOR TO AMERICAN CAR AND FOUNDRY COMPANY, OF NEW YORK, N. Y., A CORPORATION OF NEW JERSEY

CONTAINER FOR LIQUIDS OR GASES UNDER PRESSURE AND METHOD OF MAKING THE SAME

Application filed February 10, 1927. Serial No. 167,313.

Reference is had to the accompanying drawings which illustrate the preferred form of the invention, though it is to be understood that the invention is not limited to the exact details of construction shown and described, as it is obvious that various modifications thereof within the scope of the claims will occur to persons skilled in the art.

10 In said drawings:

Fig. 1 is a sectional view of the holder;

Fig. 2 is a sectional view of a modified form of the holder;

15 Fig. 3 is an enlarged fragmentary sectional view through the holder, showing the joint intermediate the ends, and

Fig. 4 is a detail sectional view of the beaded end of the inner shell of the holder.

20 It is the primary object of the present invention to provide a holder for carbonated beverages, or other liquids or gases under pressure, and one in which the danger of corrosion is reduced to a minimum, and more particularly the invention contemplates the provision of a tank.

It is a further object of the invention to provide a tank having an inner shell of substantially non-corrosive metal.

Another object of the present invention is 30 to provide a tank having an inner shell which is formed of a suitable acid resisting metal. A still further object of this invention is the provision of a tank having a lining formed of aluminum or metal possessing the properties of aluminum. Still another object of 35 the invention is the provision of a tank having an inner shell of aluminum or other substantially corrosion resistant metal and an outer shell of steel or the like shrunk thereon whereby to firmly unite the two shells.

40 Another object of this invention is to provide a tank for carbonated beverages, liquids or gases under pressure having an inner shell formed of united sections, and an outer shell formed of united sections shrunk onto the inner shell to provide a close uniting of the two shells, and to effect a strong and durable structure.

45 Referring more particularly to the drawings, the present invention comprises broadly

a main body portion formed of substantially cylindrical sections A and B constituting an inner and outer tank or shell, respectively. This body portion is provided with end closures, as shown clearly in Fig. 1, said 55 closures being designated as C and D.

The inner shell A may be formed of any suitable or desired corrosion resistant metal, and is here mentioned as formed of aluminum which has been previously drawn to shape, 60 and comprises sections 1 and 2, respectively, joined together end to end at the outwardly extending marginal flanges 3 and 4. To form a leak proof joint, the said flanges 3 and 4 are welded, soldered, or otherwise secured together throughout the entire circumference, as shown at 5 (see Fig. 3). While the drawings show the sections A and B as substantially cylindrical, it is obvious that the sections may be shaped as desired. Referring to 65 Fig. 1, the section 2 of the container or shell A is reduced at one end, forming a neck 6 defining an opening 7 which is normally closed by the cap or closure D, heretofore mentioned. The marginal edge of the section 2 is beaded 70 as shown at 8, the head resting upon the marginal edge of the reduced end 9 of section 9^a of the steel outer shell B, and the opposite end of this section 9^a is outwardly flanged as 75 shown at 10.

The outer container B is formed preferably of steel or other like metal and includes, in addition to the section 9^a, the section 11 which has one end thereof flanged outwardly as 80 shown at 12, and in the finished product the flanges 10 and 12 are connected together by suitable means such as rivets 13 or the like.

An end closure C is provided for the tank, which is, as shown, substantially convex in shape and includes a steel main portion 14 having a lining 15 of aluminum or other like material secured thereto in any suitable manner. The main portion 14 terminates in a cylindrical hoop shape portion 16, and this closure C is so formed that a nice fit is obtained between the adjacent end of the body portion of said closure, with the lining 15 in engagement with the aluminum of section 1 of the inner container. Preferably the lining 15 is welded, soldered, or otherwise securely 85 100

connected to the inner shell 1 to form a circumferential leak proof joint. The closure C is further provided with angularly arranged integral reinforcing ribs 16^a, for an obvious purpose.

5 The cover D, shown clearly in Fig. 1, is preferably lined with aluminum or other corrosion resistant material as indicated at 17, and said cover is provided with angularly arranged reinforcing ribs 18. For retaining this cover or end closure in engagement with the tank, bolts 19 or the like are provided which extend through the material of the cover and through a flange 20 formed integral with a collar 21 which is preferably shrunk around the neck 6. The lining 17 is of such dimensions that it overlaps the beaded end of section 2 of the inner container, and by drawing the cover into closed engagement 10 with the adjacent end of the tank it will be obvious that a substantially leak proof joint is provided between said cover or closure and the interior of the tank. Adjacent each end of the tank a ring 22 is provided, which is 15 preferably shrunk onto the tank after the same has been formed; said rings 22 being of such dimensions that when the tank is resting horizontally as shown in the drawings, the joint intermediate the end of said 20 tank will be protected, further such rings serve as a means for rolling the tank when desired, and also furnish a satisfactory means for preventing damage to the tank in handling and in transportation.

35 Referring now to Fig. 2, in which is shown a modified form of tank, it can be seen that the tank disclosed in this figure is fundamentally similar to the tank disclosed in Fig. 1, but it differs, however, in that the tank shown 40 in this figure is provided with only one end closure, the opposite end being formed integral with a section of the main body portion.

The tank of Fig. 2 comprises an inner shell 45 E and an outer shell F, the inner shell being formed of aluminum or other like material drawn to the desired shape, and consisting of sections 23 and 24, the section 23 being provided with a dome shaped end. The section 24 is substantially cylindrical, and each of the sections 23 and 24 is provided with outwardly extending flanges 25 and 26 which are welded, soldered, or otherwise secured together throughout their circumference 50 whereby to form a leak proof joint in the manner heretofore disclosed with reference to Fig. 1. The open end of the section E is preferably beaded as shown at 27.

The outer shell F is formed of sections 55 28 and 29, which are in close engagement with the inner shell, and said sections 28 and 29 are preferably shrunk onto the inner shell E. The open end of the tank shown in Fig. 2 is normally closed by cover 30, formed of 60 steel or the like, and said cover is preferably

lined with aluminum as shown at 31. This lining 31 is of such dimensions that it overlaps the beaded end 27, which beaded end engages the extreme open end of the section 28 of the outer shell, and the cover is normally held in place by means of bolts 32 which engage the marginal flange 32 formed on a collar 34, which is preferably shrunk onto the outer container F adjacent the open end thereof. The cover 30 is provided with reinforcing ribs 35, and the body portion of the tank is provided, adjacent each end thereof, with rings 36 which are preferably shrunk thereon, and which are of such size that the joint intermediate the ends of the tank is protected, and further they serve as protecting means for the tank to prevent damage thereto in handling and in transportation.

In addition to the structure herein shown and just described, a specific method of producing the tank is provided. In the manufacture of said tank I preferably form the two sections of the inner shell by drawing sheets of aluminum to the desired and required shape, to define the sections 1 and 2, and then these sections may be flanged at the proposed abutting ends. A suitable mandrel or former is then placed in the sections, separately, and a heated, preformed steel section of the required size and form is forced or otherwise placed over each of the aluminum sections while the mandrel is in position therein. The steel sections are permitted to cool, and it will be apparent that upon cooling the steel sections will be shrunk onto the aluminum sections with a resultant firm union and a nice fit of the aluminum and steel sections. The mandrels may then be withdrawn and the two united aluminum and steel sections are then placed together, end to end, and the abutting aluminum sections are united at the marginal flanges by welding. At this point in the method, the flanges 10 and 12 of the outer container are in the position illustrated in full lines in Fig. 3, and these flanges are then brought together as shown in dotted lines in Fig. 3 and securely retained in their abutting relation by means of rivets 13. The body portion of the tank having been thus formed, I then insert the end closure C shown 110 in Fig. 1, and weld, solder, or otherwise secure the lining 15 to the inner shell A. Following this the end closure D is applied.

Having thus described the invention, it will be apparent that a holder for carbonated beverages, fluids or gases under pressure has been provided which, due to its specific form, is greatly resistant to acid or other corrosion and said holder is strong and durable due to the fact that the outer container or shell has been shrunk onto the inner container or shell.

What is claimed is:

1. A holder for fluid under pressure, comprising a fluid-tight aluminum container having a steel shell shrunk thereon.

2. A holder for fluid under pressure, comprising a container formed of aluminum and having one open end, a closure for the opposite end, said closure having a lining of aluminum, a removable cover for said open end, and a steel shell shrunk on said aluminum container. 70
3. A holder for fluid under pressure comprising an inner container the body portion of which is formed of sections firmly united end to end, and an outer shell formed of sections shrunk onto said inner container and united end to end. 75
4. A tank comprising an aluminum container formed of sections firmly united end to end, and an outer shell formed of steel sections shrunk onto said aluminum container and united end to end. 80
5. A tank comprising a container formed of sections of substantially corrosion resistant material welded together end to end and having an outer shell formed of steel sections complementary with said first named sections and shrunk thereon, said steel sections being 90 united end to end.
6. The method of making tanks or the like which comprises drawing sheets of aluminum to form sections of an inner container, welding said sections together, and then shrinking a pre-formed shell onto said inner container. 95
7. The method of making tanks or the like which comprises drawing sheets of non-corrosive metal to form sections, flanging one end of each of said sections, welding the flanges of the sections to each other whereby to connect said sections, shrinking a section of material of greater strength than said first named sections onto each of the latter, and then connecting said second named sections to each other whereby to form an outer shell. 100
8. The method of making a tank which comprises drawing aluminum to form flanged cylindrical sections, shrinking a flanged steel shell on each aluminum section, arranging the sections end to end and finally connecting the flanges of the aluminum sections and the flanges of the steel sections. 105
9. The method of making a tank which comprises drawing aluminum to form cylindrical sections, shrinking a shell on each section and then uniting the several aluminum sections and the several shells. 110
10. A tank comprising an inner container formed of united preformed sections each having a steel shell shrunk thereon, the steel shells being united. 115
11. In a tank, an inner container comprising preformed drawn aluminum sections having abutting united flanges, a sectional outer container shrunk on said inner container and means connecting the sections of the outer container adjacent the united flanges of the inner container. 120
12. A tank comprising sections united end to end, each thereof consisting of a preformed inner shell of corrosion resistant metal possessing the properties of aluminum, and a preformed outer shell of metal of greater hardness than the metal of the inner shell. 125
13. In a tank, an inner container comprising preformed aluminum sections having abutting welded flanges, a steel shell shrunk on each of said aluminum sections and having outwardly extending meeting flanges and means connecting said outwardly extending flanges. 130
14. A tank comprising a container formed of drawn aluminum and having one open end, a closure for the opposite end, said closure having a lining of aluminum, a removable cover for said open end, and a steel shell shrunk on said aluminum container. 135
15. A tank comprising a container formed of drawn aluminum sections preformed to shape and united end to end and having at least one open end, a closure for the opposite end, said closure having a lining of aluminum, a removable cover for said open end, and a sectional steel shell shrunk on said aluminum container. 140
16. A holder for fluid comprising a fluid tight inner container and an outer shell arranged thereover, said inner container being retained against movement relative to the outer shell by pressure exerted radially thereagainst by said outer shell. 145
17. A holder for fluid comprising a fluid tight inner container formed of cylindrical sections united end to end and each having an outer shell secured thereto by the tension of the material forming said shell. 150
18. A holder for fluid comprising connected units each comprising an inner cylindrical section and an outer shell retained thereto by the tension of the material forming said shell. 155
19. A holder for fluid under pressure comprising an inner container the body portion of which is formed of sections of corrosion resistant metal connected together at their meeting ends and an outer shell formed of metal sections shrunk onto the inner shell sections and united end to end. 160
20. A holder for fluid under pressure comprising an inner container the body portion of which is formed of sections of corrosion resistant metal connected together at their meeting ends and an outer shell formed of flanged steel sections shrunk upon the inner container sections and united end to end at their flanges. 165
21. A holder for fluid under pressure having a body portion formed of flanged sections the flanges of which are connected, and an outer shell formed of sections having flanges lapping and enclosing the first named flanges, said outer shell sections being shrunk onto 170

the inner shell sections and united end to end through adjacent flanges.

22. A holder for fluid comprising an inner shell formed of sections united end to end, outer shell sections retained on the inner sections by pressure exerted radially against said inner shell by said outer shell sections and an end closure therefor.

23. A holder for fluid comprising a body portion formed of corrosion resistant metal and an outer metallic shell held thereon by pressure exerted radially thereagainst by said outer shell.

24. A holder for fluid comprising a body portion formed of sections of corrosion resistant metal connected together near their ends and held under radial compression by an outer shell wholly enclosing said first named sections.

25. A holder for fluid comprising a body portion formed of sections of corrosion resistant metal connected together near their ends and held under radial compression throughout their entire outer area by sections of another metal having a higher melting point.

26. A holder for fluid comprising an inner body portion formed of a corrosion resistant metal capable of melting at a relatively low temperature and an outer shell formed of metal incapable of melting at such low temperature held thereon in tension so as to place the inner body portion under substantially uniformly distributed pressure.

35 In witness whereof I have hereunto set my hand.

JOHN J. McBRIDE.
